US00D727937S

(12) **United States Design Patent**
Prajapati et al.

(10) **Patent No.:** **US D727,937 S**
(45) **Date of Patent:** ** *Apr. 28, 2015

(54) **DISPLAY SCREEN WITH GRAPHICAL USER INTERFACE**

(71) Applicant: **Microsoft Corporation**, Redmond, WA (US)

(72) Inventors: **Gaurang Prajapati**, Redmond, WA (US); **Jon Nicolas Myette**, Seattle, WA (US); **Gautam Satalkar**, San Jose, CA (US); **Peiyu Liu**, Seattle, WA (US)

(73) Assignee: **Microsoft Corporation**, Redmond, WA (US)

(*) Notice: This patent is subject to a terminal disclaimer.

(**) Term: **14 Years**

(21) Appl. No.: **29/436,851**

(22) Filed: **Nov. 9, 2012**

(51) LOC (10) Cl. **14-04**

(57) **CLAIM**

The ornamental design for a display screen with graphical user interface, as shown and described.

DESCRIPTION

The FIGURE is a front view of a display screen with graphical user interface showing our new design.

The broken line showing of the text and the remainder of the user interface and display screen is for environmental purposes only and forms no part of the claimed design.

1 Claim, 1 Drawing Sheet
